UNITED STATES PATENT OFFICE.

ANDREW J. HOPKINS, OF ROCHESTER, NEW YORK.

PUMP.

SPECIFICATION forming part of Letters Patent No. 433,406, dated July 29, 1890.

Application filed January 8, 1886. Serial No. 187,986. (No model.)

To all whom it may concern:

Be it known that I, ANDREW J. HOPKINS, a citizen of the United States, and a resident of Rochester, in the county of Monroe and State 5 of New York, have invented certain new and useful Improvements in Pumps; and I do hereby declare that the following is a full, clear, and exact description of the invention, which will enable others skilled in the art to 10 which it appertains to make and use the same, reference being had to the accompanying drawings, which form a part of this specification, and in which—

Figure 1 is a side view of my improved pump. 15 Fig. 2 is a vertical sectional view of the same. Fig. 3 is a horizontal sectional view on line $x-x$, Fig. 1. Fig. 4 is a similar view on line $y-y$, Fig. 2; and Fig. 5 is a perspective view of the pump as it is placed in a well ready 20 for operation.

Similar letters of reference indicate corresponding parts in all the figures.

My invention has relation to double-acting pumps; and it consists in the improved construction and combination of parts of the 25 same, as hereinafter more fully described and claimed.

In the accompanying drawings, the letter A indicates the pump-cylinder, which is provided 30 at diametrically opposite sides with side tubes B and C integral with the pump-cylinder.

The piston D is provided with packing-disks E, having their flanges turned in opposite directions, and is secured to the piston-rod F, which passes through a central stuffing-box G in the head II of the pump. This head is formed to correspond to the shape of the upper end of the cylinder, which is provided 35 with a flange I, and the head is formed with a knee or curved channel J, one end of which opens through the head into the pump-cylinder, while the other end of the knee, which is integral with the head, opens into the upper end of the inlet side tube B. A valve K is secured with its inner end to the center of the inner side of the head, having a perforation L for the passage of the piston-rod, and the free end or flap of this valve plays upon 40 the opening of the knee in the head of the cylinder.

The bottom M of the pump-cylinder is formed

with a socket N, into which the suction-pipe O is secured, and with a channel P, which opens into the socket for the suction-pipe and 55 into the lower end of the inlet side tube, the aperture of the said curved channel registering with the lower end of the side tube. The bottom is secured to the flange Q at the lower end of the cylinder, corresponding in shape 60 to the same, and the central aperture R in the bottom, which enters the socket for the suction-pipe, is covered by an inwardly-opening valve S, secured at one side to the side of the aperture, and having preferably a 65 weight T secured to it to insure its more perfect action in closing upon the aperture.

The delivery side tube C has an opening U at its lower end, by means of which it communicates with the lower end of the pump-cylinder, and the upper end of the tube is enlarged to form a chamber V, having an aperture W communicating with the upper end of the pump-cylinder, and a top aperture X, which registers with an aperture in the head 70 of the cylinder, which aperture is extended upward in a socket Y, into which the delivery-pipe Z is secured.

The aperture W of the chamber communicating with the upper end of the cylinder and 80 the aperture A' at the upper end of the tube and at the bottom of the chamber form valve-seats, upon which the leaves or wings of a valve B' play. This valve consists of the metal frame D' and a leather packing C, riveted or otherwise secured to it, and is formed with a round back b', and with wings or leaves diverging from said round back to form a V shape with their outer edges spread apart, the angle between said leaves being less than the angle 90 between the base and side walls of chamber V, whereby the valve may rock between said walls, and whereby each of the said wings will form an inclined bearing-surface for the passing water, as will be understood from the 95 drawings. It will be seen that in operation the valve is placed loosely in chamber V, with its round back arranged to rock or fulcrum at the juncture of the side and base walls of such chamber, the valve being alike 100 at both sides, so it can be reversed side for side, if desired, and so that no matter whether one or the other wing be placed next the opening W the valve will operate properly,

thus avoiding the necessity of any care in setting the valve. It will also be noticed that when one wing of the valve is seated its other wing projects across the line of the opening 5 it controls, and being in the path of the water passing through said opening is operated upon with great force, and the valve is consequently firmly seated on the opening it closes. In consequence of the rounded back 10 of the valve it is enabled to rock freely, so that the slightest pressure of water is sufficient to seat it on one or the other opening or valve-seat.

When the valve is placed in chamber V 15 and the cap-plate is secured on said chamber, the valve will be held in the chamber so it may freely rock and yet so it cannot get displaced. It will now be seen that as the piston is reciprocated the water will alternately enter 20 through the central aperture in the bottom of the cylinder, raising the valve upon the same or through the curved channel and through the inlet side tube and through the curved channel in the head of the cylinder, 25 forcing the valve at the head down, and the water will alternately be forced directly into the chamber having the V-shaped valve through the aperture communicating between the upper end of the cylinder and the chamber or through the delivery side tube and up 30 through the aperture in the bottom of the chamber, the force of the water entering by one aperture forcing the valve to fit upon the opposite seat with its other wing, so that the 35 alternating current of water passing through the apertures in the chamber insures a prompt action of the valve and prevents any waste of water or of motive power in consequence thereof by immediately closing the opposite 40 aperture when the stroke is changed.

It will be noticed that the outer or bearing surfaces of the wings of the rocking valve R' are smooth, so that water impinging the same will flow off without being stopped or retarded 45 in any degree thereby; also, that the wings of the valve bear such relation to their seats W A' that the open wing of the valve in the different positions thereof is inclined with reference to the channel or port it closes, so

that the stream of water through such channel or port impinging the inclined and smooth bearing-face of the valve operates thereon with a wedging action which serves to hold the closed wing of the valve firmly to its seat. At the same time the bearing-faces of the 55 valve being smooth, so that no obstruction is offered to the free movement of the water thereon, I avoid any vibrating or chattering of the valve from the action of the water, such as would likely occur should obstructions or projections be provided on the face of the valve.

Having thus described my invention, I claim and desire to secure by Letters Patent of the United States—

The herein-described improvement in pumps, consisting in the combination, with the cylinder A and the piston operating therein, of the side tube C, extending alongside the cylinder and opening therewith at its lower 70 end; the chamber V, arranged at the upper end of the tube C and having its bottom arranged approximately horizontal, and provided with port-opening A', communicating with the tube C, and having the partition or 75 side wall between it and the cylinder provided with opening W, and the rocking valve arranged to rock at the juncture of the side and base walls of chamber V, and between the ports A' W, the said valve being formed with 80 a round back and with wings or leaves diverging from said round back toward their outer edges, and spread apart at such outer edges, the angle between the leaves of the 85 valve being less than that between the base and side walls of chamber V, whereby the valve may rock between the said walls, and whereby each of the said wings when open will form an inclined bearing-surface for the passing water, substantially as described, and 90 for the purposes specified.

In testimony that I claim the foregoing as my own I have hereunto affixed my signature in presence of two witnesses.

ANDREW J. HOPKINS.
